DESIGN FOR A SPARK PLUG

George D. Suter, Wauwatosa, Wis., assignor to Globe-Union Inc., Milwaukee, Wis., a corporation of Delaware

Application February 24, 1945, Serial No. 118,117

Term of patent 7 years

(Cl. D26—1)

To all whom it may concern:

Be it known that I, George D. Suter, a citizen of the United States, residing at Wauwatosa, in the county of Milwaukee and State of Wisconsin, have invented a new, original, and ornamental Design for Spark Plugs, of which the following is a specification, reference being had to the accompanying drawing, forming part thereof, and in which:

The figure is a vertical elevational view of a spark plug showing my new design.

The dominant features of my design reside in the portions shown in full lines in the drawing.

I claim:

The ornamental design for a spark plug, as shown and described.

GEORGE D. SUTER.
